US00D850226S

(12) **United States Design Patent** (10) **Patent No.:** **US D850,226 S**
(45) **Date of Patent:** **** Jun. 4, 2019**

(54) **TOOL YOKE**

(71) Applicant: **Wallmek i Kungälv AB**, Kungälv (SE)

(72) Inventors: **Sten Johansson**, Lycke (SE); **Niklas Wallman**, Kungälv (SE); **Martin Hasselskog**, Kärna (SE)

(73) Assignee: **WALLMEK I KUNGÄLV AB**,
Kungälv (SE)

(**) Term: **15 Years**

(21) Appl. No.: **29/604,325**

(22) Filed: **May 17, 2017**

(30) **Foreign Application Priority Data**

Nov. 22, 2016 (EM) 003477090

(51) **LOC (11) Cl.** **08-05**

(52) **U.S. Cl.**

USPC **D8/14**

(58) **Field of Classification Search**

(57) **CLAIM**

The ornamental design for a tool yoke, as shown and described.

DESCRIPTION

FIG. 1 is a perspective view of a tool yoke showing our new design;

FIG. 2 is a perspective view thereof;

FIG. 3 is a top plan view thereof;

FIG. 4 is a bottom plan view thereof;

FIG. 5 is a front plan view thereof;

FIG. 6 is a rear elevational view thereof; and,

FIG. 7 is a right side elevational view thereof.

The left side view, is a mirror image of the right side view.

1 Claim, 3 Drawing Sheets
